UNITED STATES PATENT OFFICE.

ANNA MARIE PETRULLO, OF BROOKLYN, NEW YORK.

GARTER.

1,255,630.

Specification of Letters Patent. Patented Feb. 5, 1918.

Application filed November 23, 1916. Serial No. 132,977.

To all whom it may concern:

Be it known that I, ANNA MARIE PETRULLO, a citizen of the United States, resident of the borough of Brooklyn, county of Kings, city and State of New York, have invented certain new and useful Improvements in Garters, of which the following is a specification.

This device is intended as a garter for the use of children and for that reason I have designed an article of apparel simple in construction and yet efficient and one that may be readily attached and detached whenever desired.

15 The principal feature of my device resides in the construction of that portion of the device that will be attached to a belt or to a Ferris-waist or other upper garments and I have overcome the use of objectionable 20 safety-pins which often open or break inflicting injury upon the wearer.

Further than this the means I employ for securing the garter in operative position are such that they do not cut or tear the garment 25 or other device to which they are secured.

The construction and operation of my device will be set forth as the specification progresses.

The following is what I consider a good 30 means of carrying out my invention and the accompanying drawings should be referred to for a more complete understanding of the specification which follows:

In the drawings:

35 Figure 1 shows a single garter.

Fig. 2 a plurality of garters secured to a waist band.

Similar reference numerals indicate like 40 parts in all the figures where they appear.

45 At 1, I have shown what may be termed the main body member of a garter and in my construction this member should be of woven elastic material usually termed "garter elastic" and should be of a width and thickness sufficient to provide desired strength.

To the upper end of the member 1, I secure a metallic loop member 2, formed as an eye and adapted to receive a button 3, which button is secured in a plate 4, the button 3 and the plate 4, should also be of metal.

The plate 4 is provided with an elongated perforation 5, into which I may secure an extension 6, from the body member 1.

55 At, or adjacent to, the lower end of the

member 1, I arrange a buckle 7, adjustable upon the member 1, and to the buckle 7, two depending members 8 and 9 are secured.

At the lower end of each of the members 8 and 9, I secure a loop 10, quite similar in construction to the member 2, previously described, and each of the loops 10, receive a button as shown at 11 and 12. The buttons 11 and 12 are supported by plates 13 and 14 and loops 10, buttons 11 and 12, and plates 13 and 14 may and should be made of metal.

Each of the plates 13 and 14 is retained in position by means of extensions 15 and 16 from the members 8 and 9; and in the manner well understood the stocking to be supported by my garter is engaged by the buttons 11 and 12 and the loops 10.

In operation the garter is engaged to a waist band or garment by means of the device shown at the upper end of the member 1, and the stocking by the depending members as described.

When my garter is used for retaining boys' stockings or stockings of those who do not wear Ferris-waists or similar articles of apparel a waist band may be provided and in Fig. 2, I show such a waist band which consists of a body member 18, formed of webbing or other suitable material the ends of which are joined by an adjusting buckle 19, and I prefer that button holes 20 and 21 should be provided at the back and front portions of the member 18, which button holes will receive the buttons of a shirt waist. In Fig. 2 I show metallic members of other constructions and the plate 22 although of a shape different from that of the plate 14 will serve all of the functions of the plate 14. A button 23 may be directly secured to an extension 24, from a depending member 25 and operated with a certain degree of efficiency. The shape of the loops 26 and 27, although not that of the loops 10, accomplish similar purposes, and other modifications in construction, design and operation may be made within the scope of the appended claim without departing from the principle or sacrificing the advantages of the invention.

A greater or lesser number of depending members may be provided and a greater or lesser number of garters applied to the belt if desired and it will be understood that the length of the belt and of the garter members may be varied at will.

Having carefully and fully described my invention what I claim and desire to secure by Letters Patent is:

A garter having a main body member, a loop formed therein, and an extension from said loop, a metallic loop secured in the loop of said garter, and a plate provided with a slot secured in the extension from said body member, a stud upon said plate adapted to be engaged with said metallic loop; a plurality of suspended members each having a loop formed therein, and an extension, a plate secured to each said extension, and a metallic loop secured in the loop of

each said suspended member, and a button 15 upon the said plates adapted to be engaged by said metallic loops; a buckle movable upon said body member secured to said suspended members, to adjust said suspended members in longitudinal relation with said body member, all combined for joint operation as herein specified.

Signed at New York city, county and State of New York, this 6th day of November, 1916.

ANNA MARIE PETRULLO.

Witness:

CHARLES PETRULLO.
